United States Patent Office

Des. 214,493
Patented June 24, 1969

214,493

ARM CHAIR

Arthur W. Ellsworth, South San Gabriel, and Robert K. Fujioka, Los Angeles, Calif., assignors to Samsonite Corporation, Denver, Colo., a corporation of Colorado

Continuation-in-part of design application Ser. No. 85,609, June 7, 1965. This application Sept. 18, 1967, Ser. No. 9,152

Term of patent 14 years

Int. Cl. D6—01

U.S. Cl. D15—1

FIG. 1

FIG. 2

FIG. 3

FIG. 4.FIG. 5.FIG. 6.

FIG. 1 is a perspective view, showing the front and one side, of an arm chair embodying our new design, the central portion being broken away to indicate that the width of the chair is indeterminate;

FIG. 2 is a side elevation showing the opposite side of the arm chair of FIG. 1;

FIG. 3 is a rear elevation of the arm chair of FIG. 1;

FIG. 4 is a perspective view, showing the front and one side, of an arm chair also embodying our new design, the central portion being broken away to indicate that the width of the chair is indeterminate;

FIG. 5 is a side elevation showing the opposite side of the arm chair of FIG. 4; and

FIG. 6 is a rear elevation of the arm chair of FIG. 4.

This application is a continuation-in-part of our earlier filed application Serial No. D.85,609 filed June 7, 1965, and now Patent No. D.208,698.

We claim:

The ornamental design for an arm chair, as shown and described.
